UNITED STATES PATENT OFFICE.

GUSTAVE M. FAUSER, OF ARDSLEY-ON-HUDSON, NEW YORK, ASSIGNOR TO T. R. GOOD-LATTE & SONS, (INC.), OF DELAWANNA, NEW JERSEY, A CORPORATION OF NEW JERSEY.

DESIGN FOR A TABLE COVER OR ANALOGOUS ARTICLE.

Application filed November 23, 1925. Serial No. 15,518. Term of patent 3½ years.

To all whom it may concern:

Be it known that I, GUSTAVE M. FAUSER, a citizen of the United States, residing at Ardsley-on-Hudson, in the county of Westchester and State of New York, have invented a new, original, and ornamental Design for a Table Cover or Analogous Article, of which the following is a specification, reference being had to the accompanying drawing, forming part thereof.

The figure is a plan view of a table-cover, showing my new design, partly in outline, with slightly more than a quarter section in full lines, the portions shown in full lines being repeated in diametrically opposite places in the portions of the design shown in outline.

I claim:

The ornamental design for a table-cover or analogous article, substantially as shown and described.

GUSTAVE M. FAUSER.
